Attorney

UNITED STATES PATENT OFFICE.

HERMAN G. MUELLER, OF ERIE, PENNSYLVANIA, ASSIGNOR TO SKINNER ENGINE COMPANY, OF ERIE, PENNSYLVANIA, A CORPORATION OF PENNSYLVANIA.

STEAM ENGINE.

Application filed April 8, 1921, Serial No. 459,611. Renewed February 10, 1927.

It is desirable in the operation of steam engines to provide for compression through the action of the exhaust system. Where there is a variation in the exhaust back-pressure this variation disturbs the compression. The present invention is designed to provide means for controlling the compression so as to avoid the disturbance due to variations in back-pressure.

10 The invention is illustrated in the accompanying drawings as follows:—

Fig. 1 shows a horizontal section of a portion of a cylinder.

15 Fig. 2 a side elevation of the same with the controlling mechanism in vertical section.

20 1 marks the power cylinder, 2 the piston operating therein, 3 the steam inlets, and 4 the exhaust ports. These may be of common construction. As shown they are arranged for a una-flow engine. Clearance varying cylinders 5 are connected by ports 6 with the ends of the cylinder 1. Pistons 7 are arranged in the cylinders 5 and connected 25 by a rod 8, the rod extending through a gland 9 in one of the cylinders. The pistons are at the same sides of the ports 6 so that the capacity of the cylinders 5 at the port ends of those cylinders are varied with 30 movements of the pistons 7 in the same direction.

35 The rod 8 is connected to a piston 10 in a motor cylinder 11, glands 12 being provided in the heads of the cylinder 11 in the usual manner. The cylinder has the ports 13 extending to a valve chest 14 controlled by a valve 15. Motor fluid of any convenient type is supplied through a pipe 15^a to the center of the valve 15. It will readily be 40 seen as the valve is moved one way or the other fluid is admitted to one or the other end of the cylinder 11 and the piston 10 moved so as to change the positions of the pistons 7.

45 In order to make the motor, the movable element of which is the piston 10, responsive to variations in back-pressure I provide the following mechanism for the valve 15. A piston 17 is arranged in the cylinder 16. A spring 18 opposes the movement of the piston, the spring being anchored on a bridge piece 19. A connection 20 leads from the cylinder 16 to the exhaust pipe 21, the exhaust pipe 21 leading from the exhaust ports 4 and being the main exhaust from the en-

gine. It will readily be seen that with an increase of back-pressure the piston 17 is moved against the resistance of the spring 18 and with a reduction in this pressure the piston is moved through the influence of the spring, the piston finding a point of equilibrium between the pressure of the spring and the back-pressure. The movement of the piston 17 is communicated to the valve 15 by the following mechanism: A stem 22 extends from the piston through the bridge piece 19. A lever 23 is pivotally connected to the stem 22 and fulcrumed at 24 on a lever 25. The upper end of the lever 23 is connected by a link 26 with the valve 15. 60 The lever 25 is fulcrumed at 27 on the cylinder 1 and is connected by a link 28 with the piston rod 8.

65 The operation of the device is as follows:— With an increase of back-pressure the piston 17 is moved to the right, thus moving the valve 15 to the left. Immediately motor fluid is communicated to the left of the piston 10 and this moves the pistons 7 to the right increasing the capacity of the parts of 70 the cylinders 5 in direct connection with the ends of the cylinder 1, thus increasing the clearance to correspond with the increase in back-pressure so that the compression will be thus controlled. As the pistons 7 move 75 through the action of the piston 10 the lever 25 is moved with the rod 8, moving the valve 15 to a closed position. It will readily be seen that with a given position of the piston 17 the valve 15 will be brought to closed position only with a related position of the piston 7. Consequently the movement of the piston 17 is followed by a pre-determined 80 clearance in the cylinders 5 and this varies 85 with the back-pressure.

90 95 What I claim as new is:—

1. In a steam engine, the combination of a cylinder having an exhaust system cutting off the exhaust for compression; clearance chambers connected with the ends of the cylinder; clearance varying pistons in the clearance chambers; a motor actuating said clearance varying pistons; and pressure devices subjected to exhaust back-pressure controlling said motor.

100 105 110 2. In a steam engine, the combination of a cylinder having an exhaust system cutting off the exhaust for compression; clearance chambers connected with the ends of the cylinder; clearance varying pistons in the cham-

bers; a motor actuating said clearance varying pistons; a valve controlling said motor; a pressure device subjected to exhaust back-pressure; and a valve gear controlling said valve and actuated by the pressure device and responding to movements of the clearance varying pistons whereby the clearance varying pistons are positioned with relation to the pressure device.

10 3. In a steam engine, the combination of a power cylinder having an exhaust system cutting off the exhaust for compression; clearance varying chambers connected with the ends of the cylinder; clearance varying

pistons in said chambers; a rod connecting 15 said pistons; a motor piston on said rod; a motor cylinder in which the motor piston is arranged; a valve controlling the fluid passing to the motor cylinder; a pressure device connected to the back pressure; a lever connected to the pressure device and the valve; and a second lever on which the first-mentioned lever is fulcrumed; said second lever being connected at one end to said rod and the other end having a stationary fulcrum. 20 25

In testimony whereof I have hereunto set my hand.

HERMAN G. MUELLER.
